UNITED STATES PATENT OFFICE.

FRED REED AND SAM L. INGE, OF BISBEE, ARIZONA.

CONVEYER.

1,248,714.

Specification of Letters Patent.

Patented Dec. 4, 1917.

Application filed August 29, 1917. Serial No. 188,803.

To all whom it may concern:

Be it known that we, FRED REED and SAM L. INGE, citizens of the United States, residing at Bisbee, in the county of Cochise and

5 State of Arizona, have invented a new and useful Conveyer, of which the following is a specification.

The device forming the subject matter of this application is adapted to be employed 10 in a mine for loading cars with loose material, and one object of the invention is to provide a device of this kind which will operate in a satisfactory manner in places where the vertical space or headroom is 15 limited.

Another object of the invention is to provide novel means whereby the carrier is operated and dumped.

A further object of the invention is to 20 provide novel means whereby, when the carrier is advanced, a hood at the front of the carrier will be raised, the hood constituting means for preventing the loose material from sliding out of the carrier when the carrier is retracted along an inclined skid.

With the above and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed, without departing from the spirit of the invention.

In the drawings:

Figure 1 is a diagrammatic side elevation showing a conveyer constructed in accordance with the present invention;

40 Fig. 2 is a diagrammatic top plan where- in the track is omitted;

Fig. 3 is a diagrammatic side elevation showing the carrier advanced toward the material, the carrier being in dumping po- 45 sition in Fig. 1.

The letter K designates the floor of a mine and the breast appears at L. The loose material to be removed is shown at O. A track P is mounted on the floor K of the 50 mine and is adapted to be traversed by mine cars A.

The letter Q marks a skid comprising rails, each rail including an inclined part C resting on the floor K of the mine, and a 55 horizontal part B supported on the cars A.

constituent rails of the skid may be united by braces R, the horizontal parts B of the rails being provided with stops E.

The letter D designates a carrier which 60 may be in the form of a scoop provided on its bottom with a shoe 50 adapted to traverse the floor K of the mine and to be received between the rails of the skid Q, to hold the carrier D thereon when the carrier is retracted. The bottom of the carrier D is supplied with shoulders S adapted to engage the stops E to effect a dumping of the carrier when the same is retracted. The carrier D may have rearwardly projecting handles T for guiding the carrier into the loose material O when the carrier is advanced. A hood U extends across the front of the carrier and is pivoted to the sides of the carrier as shown at V. A bail 75 W is attached to the lower edge of the hood U. A roller X is journaled on the upper edge of the hood U at the front of the carrier D. A rearwardly extended bail Y is pivoted at Z to the carrier D. 80

A support I of any desired kind is located near the breast L and carries a sheave J. The numeral F denotes a reversible operating member, which may be a drum. A flexible element G is trained around the 85 sheave J, one end of the flexible element being united by means of a hook N or otherwise with the bail W which forms a part of the hood U. One end of a flexible element H is attached by means of a hook M or in 90 any other suitable way to the bail Y which is pivoted to the carrier D. The flexible elements G and H are wound in opposite directions about the drum F.

Let it be supposed that the flexible ele- 95 ment G is under tension, as shown in Fig. 3. Then the carrier D is advanced into the loose material O and the hood U is raised. When the flexible element H is put under tension, as shown in Fig. 1, the flexible element G is slackened away and the hood U is permitted to drop. This prevents the loose material in the carrier from sliding out of the carrier when the carrier is retracted by the flexible element H into the 100 position of Fig. 1. The shoulders S on the carrier D ultimately engage the stops E on the skid Q and, under the pull exerted by the flexible element H, the carrier is tilted and its load is dumped into one of 105 the cars A.

The device herein disclosed embodies a

simple but efficient means whereby a car can be loaded with loose material in mine working, or in any other place where head room is limited.

5 Having thus described the invention, what is claimed is:—

1. In a device of the class described, an inclined skid having a stop; a carrier adapted to traverse the skid and to engage the stop; a hood extended across the front of the carrier and pivoted to the carrier; a first flexible element extended rearwardly from the carrier and constituting means for retracting the carrier onto the skid into engagement with the stop thereby to effect a dumping of the carrier; a direction-changing idler; a second flexible element trained about the idler, one end of the second flexible element being connected to the hood and constituting means for advancing the carrier and for raising the hood; and means for operating the flexible elements.

2. In a device of the class described, an inclined skid having a stop and comprising spaced rails; a carrier adapted to traverse the skid and to engage the stop, the carrier

having a shoe received between the rails of the skid; a hood extended across the front of the carrier and pivoted to the carrier; a first flexible element extended rearwardly from the carrier and constituting means for retracting the carrier onto the skid into engagement with the stop thereby to effect a dumping of the carrier; a direction-changing idler; a second flexible element trained about the idler, one end of the second flexible element being connected to the hood and constituting means for advancing the carrier and for raising the hood; and reversible rotary operating means wherewith the flexible elements are assembled.

In testimony that we claim the foregoing as our own, we have hereto affixed our signatures in the presence of two witnesses.
